2 SHEETS—SHEET 2.

UNITED STATES PATENT OFFICE.

FREDERICK C. OVERTBURY, OF NEW YORK, N. Y., AND HOWARD CARLETON PLATTS, OF RUTHERFORD, NEW JERSEY, ASSIGNORS TO FLINTKOTE MANUFACTURING COMPANY, OF RUTHERFORD, NEW JERSEY, A CORPORATION OF NEW JERSEY.

TILE ROOFING.

1,182,415.

Specification of Letters Patent.

Patented May 9, 1916.

Application filed April 7, 1914. Serial No. 830,208.

To all whom it may concern:

Be it known that we, FREDERICK C. OVERTBURY and HOWARD CARLETON PLATTS, citizens of the United States, and residents, respectively, of New York, in the county of New York and State of New York, and of Rutherford, in the county of Bergen and State of New Jersey, have invented certain new and useful Improvements in Tile Roofings, (Case C,) of which the following is a specification.

Flexible prepared roofings consisting of a foundation of felt or equivalent material, saturated and coated with waterproofing and weatherproofing compounds, have heretofore been manufactured or sold in sheet form, or in blanks for use as flat shingles. While such roofings serve an ornamental and useful purpose, they fall short of presenting the ornate appearance secured by the use of expensive curved or corrugated rigid tiles which have hitherto been cast or molded of clay or other composition. Such rigid tiles may be cast or formed of any desired thickness, and present an appearance of solidity when laid or placed upon a roof.

The object of this invention is to provide a tile which has all of the appearance of a molded or cast rigid tile, which is much cheaper in construction, which may be laid easily and without great cost, and which is weatherproof, waterproof and practically fireproof. In accomplishing these objects, we may employ in forming the tile blanks substantially the same flexible material which has heretofore been employed for flat roofing, and may use many of the standard flexible prepared roofing materials now on the market. Such flexible material consists of a base or foundation of wool felt or equivalent material saturated with a waterproofing compound such as a hydrocarbon mixture, and coated with a facing or coating of a weatherproof compound such as pitch or bitumen, or a combination of oily and resinous substances, suitably colored if desired by the addition of a pigment. Preferably the outer coating has a relatively high melting point so that it will not be unduly softened by solar heat in warm climates, and it may be applied to the saturated or impregnated foundation when rendered soft and plastic by heat, or when mixed with a volatile solvent. Prepared flexible roofing ma-

terial when so made, cannot be bent at sharp angles, particularly in cold weather, for some time after it has been made and the coating has set, without cracking or breaking the coating and thus rendering the material useless as a waterproof and weatherproof covering. Hence a difficult problem is presented, in forming tiles of such material, as such material is comparatively thin, and, when laid upon a roof, even in shingle form looks flat when viewed from a distance. We have successfully overcome these difficulties and have provided a tile formed of the material referred to, so constructed and shaped that when laid it forms a waterproof and weatherproof roof which will not leak, which presents an appearance of thickness and solidity, and has the ornamental appearance of a roofing made of clay or rigid composition tiles. It will of course be appreciated that, so far as the outline or configuration of the individual tiles is concerned, they may be made in many different forms, and secured to the roof structure in many different ways without departing from the spirit and scope of the invention.

On the accompanying drawings,—Figure 1 represents in perspective view a portion of a roof covered with one form of tile embodying our invention. Fig. 2 illustrates a plan view of the roof showing tiles of different configuration to present a more ornamental appearance. Fig. 3 represents a section on the line 3—3 of Fig. 2. Fig. 4 represents a longitudinal section on the line 4—4 of Fig. 2. Fig. 5 represents a cross section on the line 5—5 of Fig. 2. Fig. 6 illustrates a method of laying the tiles. Figs. 7 and 8 illustrate portions of tile blanks of different configuration embodying the invention. Fig. 9 represents still another form of the tile. Fig. 10 represents a section on the line 10—10 of Fig. 9. Fig. 11 (Sheet 1) represents a magnified conventional section through the bent or hinge portion of a blank. Fig. 12 shows in edge view two overlapping tiles having concavo-convex hollow ribs or ridges.

All of the forms of tile which we have illustrated are characterized by their provision with one or more longitudinal ridges or corrugations formed by bending the blank, so that, when the tiles are laid, these ridges or corrugations register, and form

continuous ridges or corrugations on the roof. These ridges or corrugations may form sharp angles or may be curved without departing from the spirit and scope of the invention; but, for the purposes of the present case, we have illustrated them as angular in cross section. Furthermore as illustrated, each tile is provided at the lower edge, which will be exposed when laid, with a doubled or folded under portion which gives the tile an appearance of thickness and solidity. Preferably, although not necessarily, the exposed edges are secured to the supporting structure by fasteners which engage the folded under edge, and which are themselves covered or concealed by the body of the tile.

For the reasons which we have hereinbefore presented, which preclude the bending and shaping of the tiles "on the job", we form each tile with a series of bends or folds while it is soft and plastic, and thus permit the coating to set or harden, after which it is possible to manipulate the folded portions without cracking or breaking the coatings.

By suitable machinery the tile blanks are cut from a sheet of the roofing material referred to with the desired outline or configuration as shown for example in Figs. 10 and 13. In this case, it is substantially rectangular, but with a tab or projection 14 on its lower edge. The coating (or coatings if both sides of the blank be provided therewith) is then softened by the application of heat or a suitable solvent, and the tab 14 is folded under the body of the blank, as shown conventionally in Fig. 11. In this figure, the foundation *a* of wool felt or other equivalent absorbent material of the desired thickness (preferably two-ply or three-ply, saturated with a waterproofing compound of hydrocarbons or the like, having a relatively low melting point so as to remain relatively soft at usual atmospheric temperatures) and coated or faced on both sides with relatively thick coatings or layers *b*, *c* of pitch or bitumen or other weatherproof compound having a relatively high melting point as previously pointed out. When the blank is bent or folded, the coatings being soft and plastic by heat or by the application of a suitable solvent along the line of the bend or fold, the coating *b* is stretched or elongated at *b'*, and the coating *c* is compressed or compacted, and more or less crimped or corrugated at *c'*. The blank is then cooled, or exposed, to permit the coatings to set in their respective stretched and compacted conditions at the bend. After the coatings have set, it will be seen that a hinge or flexible portion is formed at the bend or edge of the fold, and that the portion 14 may be swung about the hinge without the exposed coating *b'* cracking and

breaking, unless of course there is undue manipulation. Each blank is in the same manner formed with longitudinal bends or folds between its longitudinal side edges, each folded portion being connected to the adjacent portion or portions with the flexible hinges or hinge portions just described.

In Figs. 9 and 10, the tile there shown has along one side edge portion three of said longitudinal hinges 15, 16 and 17, and along its other side edge portion two hinges 18 and 19. After these are formed and the stretched and elongated exposed coatings at the bends or hinges have been set, the blanks may be flattened and packed for shipment. In the forms shown, each blank has at its longitudinal edges at least two marginal portions 20, 21 or 22, 23, which may be bent to form an angular ridge or corrugation on the roof. But along one edge each blank has also an outer third portion 24 connected by the hinge 17 with the portion 16. This is provided so that it may be overlapped by the portion 23 of the next adjacent blank and extend up into the cavity or groove formed by the portions 23, 22.

In Fig. 12 each blank has two hinges 31, 32 and curved portions or ribs 33, 34, which are formed by rollers or other suitable means while the coatings are soft and plastic. These form curved concavo-convex ribs or ridges when the tiles are laid as subsequently described.

In laying the tiles upon a rigid structure, such as the wooden boards with which the partially formed roof is usually provided, a row of tiles is laid horizontally across the roof, with their side edges overlapped as described, and so that between the body portions of two adjacent tiles are formed two upstanding concavo-convex angular ridges or ribs which project above the surfaces of the body portions as clearly shown in Fig. 1. Each tile may be first placed upon the structure with its face downward and with the tab or projection 14 extending toward the ridge-pole as shown. Then fastenings, such as nails 24, are driven through the tab into the supporting structure, and the body of the sheet is then folded upwardly and rearwardly so as to cover the fastenings and the holes made thereby. In lieu of nails, we may employ right-angle-fastenings 25, such as shown in Fig. 6, each consisting of a shank and an elongated head at a right angle thereto, so that the edge of the tab 14 may be slipped thereunder without the shank penetrating the tab. This is the more convenient fastening to use, when tiles such as shown in Fig. 7 are laid. Of course, however, any other suitable form of fastening may be employed in lieu of those described. With the tiles shown in Fig. 12, there are single ribs or ridges between the tiles instead of double ribs or ridges as in Fig. 1. 130

- It is quite evident that those portions of the tiles, which are exposed by laying, may be formed or shaped with any ornamental configuration as shown in Figs. 2, 7 and 8.
- 5 In Fig. 7, the lower edge of the body portion is slit as at 25, and the two triangle tabs fold under and flexible hinges are formed at the folds as at 27. Or, if desired, the lower edge portion of the tile may be curved 10 as shown at 28 in Fig. 8. It may be preferable to have the crimped or corrugated portions provided with a doubled under edge, in which case that portion of the tile will be formed with tabs 29, 29, as shown in Fig. 15 9, which are doubled under at the same time that the tab 14 is doubled under, and the longitudinal folds formed subsequently. Sometimes the lower corner of the overlapping portion 23 may be cut off as shown 20 at 30 in Fig. 9 and in Fig. 2. When the tiles have been laid as described, the ridges or hollow ribs of each horizontal row of tiles overlap and form continuations of the corresponding ribs or ridges of the next adjacent row of tiles. Preferably the individual tiles are of such length that when laid each tile overlaps, and is overlapped by two adjacent tiles longitudinally of the hollow ribs or ridges.
- 25 30 It will be evident to persons skilled in this art that numerous variations in size, shape and construction may be adopted in tiles of this general character without departing from the spirit and scope of the invention.
- 35 We should point out that additional fastenings may be passed through the V-shaped portions of the corrugations into the supporting structure, at points where they will be covered by overlapping tiles, for insuring 40 the attachment of the side edges of the tiles to said structure.
- We do not claim herein broadly the bending of a piece of coated waterproof or weatherproof material while the coating is soft and 45 plastic to form a flexible hinge portion, as

that is claimed in Letters Patent No. 1,104,998, filed March 18, 1913, by F. C. Overbury, and granted July 28, 1914.

When the tiles are laid, as shown in Fig. 1 for instance, they are arranged in horizontal and in vertical (relatively) rows 50 with each tile overlapping the adjacent lower tile and underlapping adjacent upper tile in each vertical row, and lapping the adjacent tiles in the same horizontal row. 55 The lapping side portions or raised ribs interlock, as it were, such ribs on one tile registering in alinement with the tiles in the same adjacent rows.

What we claim is:

60 1. A roofing tile formed of flexible waterproof material having a weatherproof coating, and comprising a body portion formed with a longitudinal bend or fold forming a flexible hinge and with the coating stretched at the bend, whereby the tile may be placed upon the roof with an upstanding portion to form a ridge or rib.

65 2. A flexible roofing tile formed of a flexible non-metallic foundation coated with a weatherproof material adapted to be made plastic, said tile comprising a body portion and side portions flexibly connected by bends or hinges to said body portions, the exterior coating being stretched and elongated at said hinges or bends.

70 75 3. A flexible roofing tile formed of a flexible non-metallic foundation coated with a weatherproof material adapted to be made plastic, said tile comprising a body portion, a doubled under tab at its lower edge, and with a flexibly connected shaped side portion adapted to form an upstanding rib.

In testimony whereof we have affixed our signatures, in presence of two witnesses.

FREDERICK C. OVERBURY.
HOWARD CARLETON PLATTS.
